DIFFERENTIAL ADJUSTMENT

Stephen Crum, Minneapolis, Minn., assignor to
 Minneapolis-Honeywell Regulator Company,
 Minneapolis, Minn., a corporation of Delaware

Application October 13, 1939, Serial No. 299,316

15 Claims. (Cl. 200—139)

This invention is directed broadly to a novel type of differential adjustment and deals more specifically with a means for adjusting the operating differential of a condition responsive mercury switch.

Differential adjustments are old and well known in the prior art, but these adjustments are either difficult to make or else are so located as to require expert manipulation in order to avoid injury to the device. For example, where the differential adjustment is made by varying the relative positions of two members which are moved by the condition responsive element and which form a part of the driving connections between the element and the switch, the actual adjustment by means of a screw-driver or wrench is very apt to distort and strain the condition responsive element due to the fact that the element is usually comparatively delicate and a relatively great force must be applied to release the part to be adjusted and then fix it in its new position. Great care must be taken under these circumstances because any accidental movement of the screw-driver or wrench may so distort the responsive element as to give it a permanent set which would destroy the calibration of the switch.

Adjustments of condition responsive switches are frequently made by unskilled persons who are unfamiliar with the construction of the devices and who would therefore not be likely to exert the care and skill necessary for making these adjustments. It is therefore a primary object of this invention to provide a condition responsive switch having a means for adjusting the differential of operation which is simple in construction, easy to manipulate, and which cannot damage either the driving connections or the responsive element no matter how carelessly the adjustment is made.

Another object of the invention is to provide a condition responsive switch in which the movable parts of the differential adjustment are mounted directly to a fixed plate within the instrument casing, and not directly connected to any movable part of the mechanism, whereby excessive strains cannot be placed on the condition responsive element by manipulating the differential adjustment.

Another object of the invention is to provide a device of the above type having a two-way strain release connection between the condition responsive element and the switch so as to prevent excessive strain on the element on overrun of the condition value.

A further object of the invention, as exemplified in a modification, is to provide for an

overrun of the operating connections and mercury switch on abnormally great variations in the condition value thereby eliminating the necessity for a strain release connection to the condition responsive element.

Further objects reside in the combination of elements and the details of construction.

For a clearer understanding of the invention reference is made to the specification taken in the 10 light of the accompanying drawings in which

Figure 1 is a side view taken partially in section of one form of my invention as applied to a thermostatically operated switch having a horizontal mounting.

Figure 2 is a front elevation of part of the mechanism shown in Figure 1.

Figure 3 is a rear elevation of the mechanism shown in Figure 2.

Figure 4 is a detail view of the scissors type strain release,

Figure 5 is a rear elevation partly in section of my invention as applied to a thermostatically operated switch having a vertical mounting.

Figure 6 is a front elevation of the modification shown in Figure 5.

Figure 7 is an exploded view of a further modification of my invention as applied to a horizontal mounting.

Figure 8 is a rear view of a portion of the mechanism shown in Figure 7, and

Figures 9, 10 and 11 are more or less diagrammatic views showing the mechanism in various positions of operation.

The invention has been illustrated and will be 35 described in the following specification as a bimetallic thermostat actuating a mercury switch. It will be readily appreciated however that other types of condition responsive elements may be substituted for the bimetallic thermostat and furthermore it is not essential that the switch to be actuated be a mercury switch.

Referring first to Figure 1 of the drawings the reference numeral 10 indicates generally a casing which houses the mechanism of my present invention. This casing comprises a base 11 and a cover 12, the cover being provided with projections such as is shown at 13 which frictionally engage in holes 14 in the base 11 to maintain the cover in position on the base.

The base 11 is provided with an opening 15, and a guard 16 is connected to the base 11 around the hole 15 and projects rearwardly from the base. Rotatably mounted in the hole 15 is a sleeve 17 which is connected at its inner end to an adjusting disc 19. The adjusting disc is provided with

an annular depression 20 which is adapted to slide frictionally on a bearing washer 21 which lies against the back of the base 11 about the hole 15. A guide sleeve 22 is provided with a narrow portion which is inserted within the end of the sleeves 17 and a wide portion 23 against which a washer 24 seats. A retaining spring 25 is provided with a hole 26 which receives the end of the member 22 and the ends of the retaining spring 25 are engaged in holes in opposite sides of the base 11 as illustrated in my copending application Serial No. 299,315 and filed October 13, 1939.

The outer end of the sleeve 17 has an inturned portion 30 and a projection 31 to which one end of a bimetallic helix 33 is connected by means of the screw 32. The other end of the bimetallic helix 33 is connected to an actuating rod 34 by means of the screw 35 and this actuating rod extends through a hole in the portion 30 of the sleeve 17, through the sleeve 17 and the guide sleeve 22 and within the casing 10. The inner end of the rod 34 carries an actuating member in the form of a scissors type strain release generally indicated at 37.

The scissors type strain release is in the form of a hub 38 having a narrow stem portion 39 to which an L-shaped stop 40 is rigidly connected. Rotatably mounted on the stem portion 39 are a pair of fingers 41 and 42. A resilient spring is wound several times around the stem 39 and one end of the spring 43 is inserted through a hole in the member 41 and the other end of the spring 43 is inserted through a hole in the finger 42, the effect of the spring being to resiliently hold the fingers 41 and 42 in engagement with the L-shaped stop 40.

A plate 45 is rigidly connected to the base 11 by means of the posts 46 and 47 which are fixed to the base by means of screws 48. A mercury switch carrier 49 is pivotally mounted to the plate 45 by means of the shaft 50. The carrier 49 supports the mercury switch 51 by means of the clip 52 so that as the member 49 is rotated back and forth the mercury switch 51 is moved between open and closed positions. The mercury switch carrier 49 is provided with a rearwardly extending portion 55 and laterally extending portion 56 and a shaft 57 extending between the main portion of the carrier 49 and the laterally extending portion 56 pivotally carries a lever 58.

The plate 45 is provided with a circular opening 59 which receives the hub 38 of the strain release 37. The hole 59 has an extension which receives a pin 60 which is carried by a mid portion of the lever 58. The upper end of the lever 58 carries a pin 61 which extends between the two fingers 41 and 42 of the strain release 37. The pin 60 is free to move from one side 63 to the other side 64 of the extension of the opening 59. In order to adjust the limit of movement of the pin 60 toward the side 64 of the opening 59 a lever 66 is provided which is pivoted on a shaft 59 and a spring 67 resists rotation of the lever. This lever is provided with a shoulder 68 against which the pin 60 will rest under certain conditions of adjustment of the lever. This will be more fully described later. The lever 66 is provided with a forwardly projecting finger 70 by means of which it may be rotated about the shaft 59 and this finger cooperates with a scale 71 carried by the plate 45 which may indicate the relative adjustment of the lever.

A main adjusting arm 72 seats on a small shoulder on the guiding sleeve 22 for rotation

about the rod 34 as a center and is adjustably secured to a projection 73 on the adjusting disc 19 by means of a screw 69 which threads into a tapped hole 74 in the projection 73 and extends through a clearance slot 75 in the adjusting arm 72. The adjusting arm 72 is generally U-shaped and the forward portion is provided with a head 76 having a kerf 77 so that it may be rotated by means of a screw-driver. The head 76 projects through a hole 78 in the front of the cover so that the adjustment may be made without removing the cover. The cover may be provided with a window 79 so that a portion 80 of the arm 72 may be seen. This portion 80 may carry a scale to indicate the relative adjustment of the arm. The arm 72 is provided with a hole 81 to accommodate the blade of a screw-driver for loosening the screw 69 in order to relatively adjust the arm 72 and the adjusting disc 19.

In considering the operation of the above device let it be assumed that the temperature is at a relatively high value and that the thermostat 33 has rotated the lever 58 in a counter-clockwise direction as viewed in Figure 2 and that the mercury switch 51 is in open position. Further, let it be assumed that the lever 70 is adjusted as seen in Figures 2 and 3 to permit a relative movement of the pin 60 between the shoulders 63 and 68. On a decrease in temperature the bimetallic thermostat 33 will cool and move the pin 61 on the upper end of the lever 58 toward the right as seen in Figure 2. During this time the lever 58 will rotate freely about the shaft 57 and the pin 60 which was in engagement with the shoulder 63 will move toward the shoulder 68. As this operation takes place the lever 58 is rotating freely and is having no effect upon the mercury switch carrier 49. After the pin 60 has engaged the shoulder 68 on the lever 66 this free rotation of the lever 58 can no longer take place and a further movement of the pin 61 toward the right as seen in Figure 2 will result in a rotation of the lower end of the lever toward the left as seen in Figure 2, or in other words, the lever will be rotating in a clockwise direction and the shaft 57 will be swinging about the shaft 50 as a center. This swinging motion of the lower end of the lever 58 will result in the rotation of the mercury switch carrier 49 about the shaft 50 and will result in tilting the mercury switch 51 to closed position. The rotation of the mercury switch 51 will continue until the lower end of the lever 58 strikes shoulder 82 on plate 45 and prevents further movement of the lever 58. Any further rotation of the actuating rod 34 by the bimetallic thermostat 33 will result in a separation of the stop 40 on the strain release 37 from the finger 41.

Moving the mercury switch 51 to closed position should reverse the temperature trend so that the bimetallic thermostat 33 should now begin to heat up and rotate the actuating rod 34 in the opposite or counter-clockwise direction as seen in Figure 2. The first thing this rotation accomplishes is to return the finger 41 and the stop 40 into engagement after which the strain release 37 will move pin 61 toward the left as seen in Figure 2. This movement will cause the lever 58 to rotate freely about the shaft 57 until the pin 60 engages the shoulder 63 after which the lower end of the lever 58 will swing in a direction to rotate the mercury switch carrier 49 in a counter-clockwise direction about the shaft 50 which will result in opening the mercury switch 51. Any further rotation of the rod 34 in a counter-clockwise direction will result in the stop 40 of the

strain release 37 separating from the finger 42. It will be noted that the mercury switch 51 is mounted above its pivot 50 and hence tends to remain in either of its actuated positions until it is positively moved out of it.

It will be seen that the spacing between the shoulders 63 and 68 results in a free movement of the lever 58 before it actuates the mercury switch 51. A certain definite temperature change is required in order for the bimetallic thermostat 33 to rotate the pin 61 a distance sufficient to produce this free rotation of the lever 58. This arrangement therefore provides for a definite differential of operation in the mercury switch 51 and this differential of operation may be varied by adjusting the lever 66 which varies the position of the shoulder 68 with respect to the pin 60. In other words, if the lever 66 were rotated against the stop 83, the shoulder 68 would lie in engagement with the pin 60 while that pin was also in engagement with the shoulder 63. Under these conditions the lever 58 would have no free movement and would immediately start to rotate the mercury switch 51 as soon as the pin 61 was moved by the actuating rod 34. This would be the condition wherein the differential of operation was at its minimum value. If the lever 66 were rotated in the opposite direction until the finger 10 engaged the shoulder 84 on the plate 45 then the shoulder 68 of the lever 66 would coincide with the side 64 of the hole 59 in the plate 45. Under these conditions the pin 60 would have a maximum movement between the two shoulders and the differential of operation would be at its maximum value. Obviously, the differential of operation can be adjusted to any value in between these two extreme values by the adjustment of the lever 66.

It will be observed that the plate 45 and the lever 66 which provide the shoulders between which the pin 60 operates are mounted on the casing and that the manipulation of the lever 66 cannot put any strain whatever upon the thermal element 33 except that which may be imposed thereon through the strain release 37. Therefore this differential adjustment is practically foolproof as far as damage to the instrument is concerned. The main adjustment for this instrument is accomplished by rotating the arm 72 which carries with it the sleeve 17 and one end of the bimetallic thermostat 33. Obviously, a rotation of this arm adjusts the temperature at which the thermostat 33 will actuate the mercury switch 51.

It will be noted that the temperature at which the mercury switch is moved to open position is determined only by the adjusting arm 72. The adjustment of the lever 66 does not affect this operation because the pin 60 is against the fixed shoulder 63 when the mercury switch is rotated to open position. The adjustment of the arm 66 in controlling the differential of operation affects only the temperature at which the switch 51 is reclosed. This feature is of particular value in high limit controls wherein it is desired that the scale 80 should indicate the temperature at which the switch opens regardless of the differential adjustment.

The modification disclosed in Figures 5 and 6 is directed to a device which is adapted to be mounted vertically instead of horizontal as in Figures 1 to 4. In Figures 5 and 6 the guard 16, sleeve 17, and bimetallic thermostat 33 extend downwardly from the base 11. These elements are mounted however in the same manner as in

the first modification and the adjusting disc 19 is connected to the sleeve 17 so that it may be rotated for adjusting the setting of the thermostat 33. The adjusting arm is slightly different in this modification. This arm, indicated at 89, is adjustably connected to the adjusting disc 19 in order to provide for a calibrating adjustment and is provided with an arcuate scale 90 and a forwardly projecting arm 91 to facilitate manual rotation of the disc 19. The rod 34 is rotated by means of the thermostat 33 and this rod carries a scissors type strain release 37 as in the case of the first modification.

A plate 92 is supported on posts 93 which are suitably secured to the rear of the base 11 and the plate is fastened to these posts by means of screws 94. Pivotally mounted to the plate 92 by means of a shaft 95 is a mercury switch carrier 96 which carries a clip 97 in which is mounted the mercury switch 98 shown in dotted lines in Figure 6. The lower end of the mercury switch carrier 96 has a rearwardly and laterally extending portion 100 for the purpose of supporting a shaft 101 on which the floating lever 102 is pivotally mounted. The lever 102 has a downwardly extending tongue 103 which extends between the two fingers 41 and 42 of the strain release connection carried by the rod 34. The upper end of the lever 102 is provided with a pin 105 which extends through a slot 106 in the plate 92. One end 107 of the slot 106 limits the movement of the pin 105 toward the left as seen in Figure 5 and a shoulder 108 on the differential adjusting lever 109 limits the movement of the pin 105 toward the right. The lever 109 is pivotally mounted on the plate 92 coaxially with the mercury switch carrier 96. A spring element 110 is mounted concentrically with the lever 109 and offers a frictional resistance to the rotation of the lever 109 thereby tending to maintain it in its adjusted position. The lever 109 may be rotated in a clockwise direction until finger 112 formed integrally therewith engages a shoulder 113 on the plate 92 at which time the shoulder 108 will be farthest removed from the shoulder 107 and the differential will be at its maximum. If the lever 109 is rotated until the finger 112 is limited by engagement with the shoulder 114 on the plate 92 the shoulder 108 will be moved until it is spaced from the shoulder 107 only by the width of the pin 105. This adjustment corresponds to the minimum differential.

Assume that the lever 109 is adjusted as shown in Figure 5 and that the temperature is at a relatively low value. The rod 34 has rotated the lever 102 until the pin 105 is against the shoulder 107 and will have rotated the mercury switch carrier 96 to the position shown in Figures 5 and 6 at which time the circuit through the mercury switch will be closed. On an increase in temperature the rod 34 will be rotated by means of the thermostat 33 to swing the tongue 103 of the floating lever 102 toward the left as seen in Figure 5. At this time the lever 102 will rotate freely about the shaft 101 and move the pin 105 against the shoulder 108. Further movement of the tongue 103 toward the left by the rod 34 will swing the shaft 101 toward the left about the shaft 95 which will rotate the mercury switch carrier 96 in a clockwise direction as seen in Figure 5 and cause the mercury switch to be moved to open circuit position. Any further rotation of the rod 34 will be taken up by means of the strain release 37 and will have no effect upon the lever 102. On a decrease in tempera-

ture the rotation of the rod 34 will be reversed and the strain release will first be taken up after which the tongue 103 of the lever 102 will be swung toward the right as seen in Figure 5 and the lever 102 will first pivot freely about the shaft 101 until the pin 105 engages shoulder 107 after which further movement to the right of the tongue 103 will cause the shaft 101 to swing toward the right and rotate the mercury switch carrier 96 to the position shown in Figure 5, at which time the circuit through the mercury switch 98 will be open. Any further rotation of the rod 34 will of course be taken up by the strain release 31. The mercury switch 98 remains stationary during the differential action due to the fact that it has an over center mounting and hence must be positively moved from both of its limit positions.

It will be appreciated that adjustment of the lever 109 will vary the position of the shoulder 108 and this adjustment varies the operating differential of the switch from a maximum when the shoulder 108 is farthest from shoulder 107, to a minimum where the shoulder 108 is separated from shoulder 107 only by the width of the pin 105. In the latter case there can be no lateral motion of the pin 105 and any movement of the tongue 103 will be immediately transferred to the mercury switch 98 hence the differential of operation is at a minimum under these conditions.

Here as in the first modification the adjustment of the differential is accomplished by means of the lever 103 which is pivoted to a member fixed to the base of the casing, therefore no undue strain can be placed on the thermostatic element or the moving parts when the adjustment takes place. It is also clear that one of the limits of operation may be read directly on the scale 90 and the differential adjustment does not affect this limit. In this particular case it is the temperature at which the switch is closed that is read on the scale 90 and which is not affected by the differential adjustment, hence this particular device would be suitable as a low limit wherein that limit is the one which is adjustable by the arm 91 and which may be read directly on the scale 90.

The modification disclosed in Figures 8 to 11, inclusive, is somewhat similar to the first modification described except that the parts have been so arranged that the scissors type strain release connection may be omitted. In this modification the thermostatic element mounting and the arm for adjusting the temperature setting of the thermostat are exactly the same as in the first modification. Instead of the scissors type strain release, a crank arm 120 carrying a pin 121 is adjustably mounted on the shaft 34 by means of the set screw 122. A plate 123 is rigidly connected to the base 11 by means of the posts 124 and screws (not shown). A mercury switch clip 126 is connected rigidly to a shaft 127 pivoted in the plate 123. The clip 126 carries the mercury switch 128. On the other side of the plate 123 and rigidly connected to the shaft 127 is a second crank arm 129 which is U-shaped at the bottom as shown at 130 in Figure 8 to carry a shaft 131 on which the floating lever 132 is pivotally mounted. The intermediate portion of the lever 132 is provided with an elongated slot 133 which receives the pin 121. The upper end of the lever 132 carries a pin 135 which enters a generally Y-shaped slot 136 in the plate 123. The vertical leg of the Y is formed by a shoulder 131

of the slot 136 and the shoulder 138 carried by the differential adjusting lever 139 pivotally mounted on the shaft 127. The flexible spring 140 offers a resistance to rotation of the lever 139 whereby it tends to remain in its adjusted position. The two legs 142 and 143 of the Y-shaped slot are adapted to accommodate the pin 135 as the lever 132 is rotated by the crank arm 120 in response to overrun temperatures, that is, temperatures which are well beyond the normal range of the instrument.

The lever 139 is provided with the usual finger 145 which cooperates with a scale 146 on the plate 123 to indicate the relative adjustment of the lever 139. This lever may be moved until the finger 145 abuts the shoulder 147 on plate 123 at which time the shoulder 138 will be farthest removed from the shoulder 137 and the differential of operation will be at its maximum value. The lever 139 may be adjusted until the finger 145 engages the shoulder 148 on the plate 123 at which time the shoulder 138 will be separated from shoulder 137 by a distance equal to the width of the pin 135. At this time the differential of operation will be at its minimum value.

In considering the operation of this device assume that the parts are in the positions shown in Figures 7 and 8. At this time the temperature is at a relatively low value and the mercury switch is in closed position. Moreover, the temperature has decreased well below the value at which the switch closed and the crank arm 120 has rotated in a clockwise direction to a point where it has moved the lever 132 to a position where the pin 135 is well up in leg 143 of the slot 136. As the temperature begins to increase the crank arm 120 will begin to rotate in a counter-clockwise direction as seen in Figure 7 or a clockwise direction as seen in the remaining figures. This will result in rotating the lever 132 freely about the shaft 131 and moving the pin 135 toward the left. The pin 135 will strike the opposite side of the slot 143 at which time the lever 129 will be rotated in a clockwise direction until the pin 135 clears the point 148 between the two legs 142 and 143 of the slot 136. The pin 135 will then move further to the left to engage the left-hand side of the leg 142 as shown in Figure 9. Further rotation of the crank 120 will then result in a further rotation of the crank 129 which will swing the shaft 131 in an arc to pull the pin 135 down into the vertical leg 146 of the slot 136. The crank 129 will then be rotated to a point where the mercury switch 128 will be moved to open position. It will be noted that when the rotation of the mercury switch to open position occurs the pin 135 is against the shoulder 137 of the vertical leg 146 of the slot 136. If the crank 120 should continue to rotate in the same direction the crank 129 will be rotated which will lift the lever 132 and the pin 135 in such a way that the pin 135 will pass up into the leg 142 as seen in Figure 10.

On a decrease in temperature the rotation of the crank 120 will be reversed and the pin 135 will slide down the upper edge of the leg 142 and the crank 129 will be rotated in a counter-clockwise direction. As the pin 135 clears the point 148, it will pass to the opposite side of the slot 143 as seen in Figure 11. On further rotation of the crank 120 the pin will be drawn downwardly into the leg 146 and against the shoulder 138. At this time the mercury switch will be rotated to closed position and a further rotation of the crank 120 will result in the pin 135 being

moved up into the slot 143 as seen in Figure 8. Thus it is seen that the position of the shoulder 138 determines the point at which the mercury switch is rotated to closed position.

It will thus be seen that by providing the legs 142 and 143 in the plate 123 a substantial temperature overrun is permitted in each direction without abnormal strain on the bimetallic thermostat. It will further be clear that the temperature at which the mercury switch is moved to open position is determined by the shoulder 137 and the temperature at which the switch is moved to closed position is determined by the shoulder 138. This latter temperature and hence the differential of operation of the device may be adjusted by rotating the lever 139 to adjust the position of the shoulder 138. Here again the adjustment of the main adjusting arm will vary the temperature at which the switch is opened and as the shoulder 137 is fixed this temperature may be read directly on the main scale. The adjustment of the lever 139 therefore affects only the difference between this temperature and the temperature at which the switch will be reclosed. It will also be noted that the differential adjustment is accomplished by rotating the lever 139 which is mounted directly upon the plate 123 fixed to the base 11. Therefore no strain can be placed on the thermostatic element or driving connections by the careless manipulation of the lever 139.

In these devices the casings have been made of such size that a terminal board may be mounted within them if desired. The slots 150 shown in Figure 7 have been provided for this purpose.

It will be appreciated that the above described instruments may be easily modified for independent "on" and "off" control by making the fixed stop adjustable also. In such a case temperature indicating scales could be provided for co-operation with each stop adjusting lever and the main adjustment would then be eliminated.

As many changes and modifications of this invention may occur to those who are skilled in the art it will be understood that I intend to be limited by the scope of the appended claims rather than by the specific embodiments disclosed.

I claim as my invention:

1. A device of the character described comprising in combination, a fixed support, a switch actuating member pivoted to said support, a lever pivoted at one end to said member for rotating it about its pivot, a condition responsive device for moving the other end of said lever, a fixed stop for engaging an intermediate point on said lever to limit its movement in one direction, a second stop for engaging said point to limit its movement in the opposite direction, said last mentioned stop comprising an adjusting lever pivoted to said fixed support, and means for indicating the relative adjustment of said second stop.

2. In a device of the character described, a support, a switch operating member pivoted to said support, a floating lever, a first portion of said floating lever being pivotally connected to said member whereby the latter may be rotated by the former, spaced stop means for limiting the movement in each direction of a second portion of said lever, a condition responsive device for moving a third portion of said lever back and forth whereby said lever first rotates about its pivotal connection with said member until said second portion is limited in its movement by

said stop means, after which said pivotal connection moves to rotate said switch operating member, and strain release means connecting said device and said third portion.

3. In a device of the character described, a support, a switch operating member pivoted to said support, a floating lever, a first portion of said floating lever being pivotally connected to said member whereby the latter may be rotated by the former, a fixed stop and a movable stop, said stops limiting the movement in each direction of a second portion of said lever, a condition responsive device for moving a third portion of said lever back and forth whereby said lever first rotates about its pivotal connection with said member until said second portion is limited in its movement by one of said stops, after which said pivotal connection moves to rotate said switch operating member, strain release means connecting said device and said third portion, and means for adjusting said movable stop whereby the differential of operation of said device may be varied.

4. In a device of the character described, a casing, a plate fixed to said casing, a pivotally mounted mercury switch, a rod rotated in accordance with the changes in value of a variable condition, connections between said rod and said mercury switch, means fixed on said plate comprising a pair of stops for limiting the free movement of a part of said connections for determining the differential of operation of said mercury switch, and means including a single member movably mounted on said plate for adjusting one of said stops to determine said differential.

5. In a device of the character described, a casing, a plate fixed to said casing, a pivotally mounted mercury switch, a rod rotated in accordance with the changes in value of a variable condition, connections between said rod and said mercury switch, means on said plate comprising a pair of stops for limiting the free movement of a part of said connections for determining the differential of operation of said mercury switch, one of said stops being fixed and the other comprising a lever pivoted on said plate, means to adjust said lever and thereby vary said differential of operation, and means to indicate the position of said lever.

6. In a device of the character described, a casing comprising a base and a cover therefor, a plate fixed to said base, a mercury switch carrier pivoted on said plate, a bimetallic thermostat one end of which is carried by said base, a rod, the other end of said thermostat being connected to said rod to rotate it on variations in temperature, a floating lever pivoted at one point to said mercury switch carrier, a pair of stops on said plate, a projection on said floating lever for cooperation with one or the other of said stops, and means including a strain release mechanism connecting the floating lever for movement by said rod.

7. In a device of the character described, a casing comprising a base and a cover therefor, a plate fixed to said base, a mercury switch carrier pivoted on said plate, a bimetallic thermostat one end of which is carried by said base, a rod, the other end of said thermostat being connected to said rod to rotate it on variations in temperature, a floating lever pivoted at one point to said mercury switch carrier, a pair of stops on said plate, a projection on said floating lever for cooperation with one or the other of said stops, means connecting the floating lever for

movement by said rod whereby the differential of operation of said mercury switch is determined by said stops, means for adjusting one of said stops whereby the temperature at which said switch is operated in one direction may be independently varied, means for rotating said one end of said thermostat with respect to said base, and means cooperating with said rotatable means for indicating the temperature at which said mercury switch is actuated in the opposite direction.

8. In a device of the character described, a fixed plate, a pivoted mercury switch carrier, a floating lever one portion of which is pivoted to said carrier for actuating it, a hole in said plate, a projection on said lever extending through said hole, means on said plate for limiting the movement of said projection in each direction, and condition responsive means engaging another portion of said floating lever for moving said projection into engagement with said limiting means and thereafter causing said lever to actuate said mercury switch carrier, said hole being of such size and shape as to accommodate said projection upon further movement of said lever by said condition responsive means.

9. In a device of the character described, a fixed plate, a pivoted mercury switch carrier, a floating lever one portion of which is pivoted to said carrier for actuating it, a hole in said plate, a projection on said lever extending through said hole, means on said plate for limiting the movement of said projection in each direction, and condition responsive means engaging another portion of said floating lever for moving said projection into engagement with said limiting means and thereafter causing said lever to actuate said mercury switch carrier, said limiting means including a pivoted lever, and means to adjust said lever whereby the differential of operation of said mercury switch carrier may be varied, said hole in said plate being of such size and shape as to accommodate further movement of said projection upon overrun of said condition responsive means.

10. In a device of the character described, a fixed support, a switch actuating member pivoted to said support, a lever pivotally connected at an intermediate point to said switch actuating member whereby the latter is operated by the former, a condition responsive device for moving one end of said lever, means including a strain release mechanism connecting said device and said one end, and stop means for limiting the movement of the other end of said lever.

11. In a device of the character described, a support, a switch operating member pivoted to said support, a floating lever, a first portion of said floating lever being pivotally connected to said member whereby the latter may be rotated by the former, spaced stop means for engaging a second portion of said lever to limit its movement in each direction, a condition responsive device for moving a third portion of said lever back and forth whereby said lever first rotates about its pivotal connection with said member until said second portion is limited in its movement by said stop means, after which said pivotal connection moves to rotate said switch operating member, and a two-way strain release connection between said condition responsive device and said floating lever whereby overrun of

said condition value does not place excessive strain on said device.

12. A device of the character described comprising in combination, a fixed support, a switch actuating member pivoted to said support, a lever pivoted at one end to said member for rotating it about its pivot, a condition responsive device for moving the other end of said lever, stop means for engaging an intermediate point on said lever to limit its movement and a strain release connection between said condition responsive device and said lever, whereby strain on said device due to overrun of the value of said condition after actuation of said switch is relieved.

13. In a device of the character described, a fixed support, a switch actuating member pivoted to said support, a lever pivotally connected at an intermediate point to said switch actuating member whereby the latter is operated by the former, a condition responsive device for moving one end of said lever, stop means engageable with the other end of said lever to limit its movement, and a strain release connection between said condition responsive device and said lever, whereby strain on said device due to overrun of the value of said condition after actuation of said switch is relieved.

14. In a device of the character described, a casing comprising a base and a cover therefor, a plate fixed to said base, a mercury switch carrier pivoted on said plate, a bimetallic thermostat one end of which is carried by said base, a rod, the other end of said thermostat being connected to said rod to rotate it on variations in temperature, said thermostat and rod projecting horizontally through the back of said casing, a floating lever pivoted at one point to said mercury switch carrier for movement in a vertical plane, a pair of stops on said plate, a projection on said floating lever for cooperation with one or the other of said stops, a pin extending horizontally from said lever, and a strain release mechanism on said rod comprising a pair of oppositely biased fingers extending vertically on opposite sides of said pin, said pin and strain release mechanism forming a driving connection between said rod and said lever, whereby strain on the thermostat due to overrun after actuation of said switch is prevented.

15. In a device of the character described, a casing comprising a base and a cover therefor, a plate fixed to said base, a mercury switch carrier pivoted on said plate, a bimetallic thermostat one end of which is carried by said base, a rod, the other end of said thermostat being connected to said rod to rotate it on variations in temperature, said thermostat and rod projecting vertically through said casing, a floating lever pivoted at one point to said mercury switch carrier for movement in a vertical plane, a pair of stops on said plate, a projection on said floating lever for cooperation with one or the other of said stops, and a strain release mechanism on said rod comprising a pair of oppositely biased fingers extending horizontally on opposite sides of said lever, said strain release mechanism forming a driving connection between said rod and said lever, whereby strain on the thermostat due to overrun after actuation of said switch is prevented.
